UNITED STATES PATENT OFFICE.

ARTHUR LOPEZ, OF NEW YORK, N. Y., ASSIGNOR TO THE HAMMOND TYPEWRITER COMPANY, A CORPORATION OF NEW YORK.

SHIFT-KEY ATTACHMENT FOR TYPE-WRITING MACHINES.

1,118,664.

Specification of Letters Patent. Patented Nov. 24, 1914.

Application filed July 30, 1913. Serial No. 781,958.

To all whom it may concern:

Be it known that I, ARTHUR LOPEZ, a citizen of the United States of America, residing in New York, in the borough of Manhattan, county and State of New York, have invented certain new and useful Improvements in Shift-Key Attachments for Type-Writing Machines, of which the following is a specification.

This invention relates to a shift-key attachment for typewriting machines of the Hammond type, the attachment being mainly designed for machines which are used for the Arabic, Turkish and other oriental languages, in which the alphabet, punctuation marks, etc., cannot be brought within the usual three-line type-shuttles, but in which, for example, five lines of type are required, and in which machines the shuttle-guiding anvil and its shuttle have therefore to be lifted to a greater number of levels or stages so as to provide for the increased number of lines of type on the shuttle; and for this purpose the invention consists of means by which the shift-keys for the capital letters and figures and punctuation marks are each given two separate lifting actions, thereby providing for four shifting motions from the ordinary position of the shuttle for printing the ordinary type.

In the accompanying drawings, Figure 1 represents a plan-view of the keyboard of a Hammond typewriting machine, showing the shift-keys arranged at the center of the keyboard, Fig. 2 is a vertical section on line 2—2, Figs. 1 and 3, showing the connection of the shift-keys with the shaft of the shuttle-carrying anvil, Fig. 3 is a front view of the shift-keys and adjacent parts, and Fig. 4 is a vertical section on line 4—4, Fig. 3.

Similar letters of reference indicate corresponding parts throughout the different figures of the drawings.

Referring to the drawings, *a* represents the ordinary keyboard for the Arabic or other language, *a*¹ the space-key, *a*² the capital shift-key, and *a*³ the figure shift-key, which two latter keys are arranged at the center of the key-board adjacent to and one on each side of the space-key. The key-levers *b*², *b*³ of the capital and figure shift-keys are pivoted in the usual manner and connected at their inner ends with the lower

end of the anvil-shaft *b*⁴. To the anvil *a* is applied a shuttle *c*¹ containing the required number of type for the language to be written, which type are arranged in five rows, one below another, the shuttle being 60 shiftable on the anvil by the same means as heretofore employed in Hammond typewriters. As a greater range of lifting of the anvil is required, than in former machines, it is necessary that the capital shift-key have a two-fold lifting motion, one from the ordinary normal position of the key to the second row of the shuttle and a second motion for the third row of the shuttle, likewise the figure shift-key requires two motions, one for the fourth row of characters and one for the fifth row of characters on the shuttle. These two motions are controlled as to each lever, the first one by an adjustable stop-screw *s* below the 70 key-lever and the second motion by shifting the key on the key-lever in backward direction, the key-lever being slotted at *e* for this purpose and a spring *e*¹ being interposed between the shank of the key and the end of the slot, so as to permit the backward shifting of the key on the key-lever and the lowering of the same into contact with a second adjustable screw-stop *e*², adjacent to the first stop. Motion of the key in outward direction on the key-lever is limited by abutment of a stop-pin *i* carried by the key-shank with the front end of its slot *i*¹ in the lever. The capital and figure shift-keys can be locked in the first lowered position resting on the longer stop *s*, or in the second position resting on the second screw-stop *e*², the key being locked when in first lowered position by means of a fulcrumed stop-lever *f*, which is provided with a button or knob at the upper end and an enlarged face at the lower end, and a stop-pin *f*² for holding it in unlocked position for permitting the use of the machine for printing the characters in the first row of the shuttle. 90 The shift-key levers are guided in slots *f*³ of the front key-guiding bar *f*¹, said slots being extended in downward direction to permit of the extra play of the key-levers, and provided at their lower ends with recesses 105 *g* for permitting the entering of the shanks of the keys into said recesses and holding thereby the key in lowermost position when it is desired to print a number of letters in either the third or fifth rows, respectively. 110

By the means described, the extra lifting motion required for the shuttles for languages having a larger number of rows of type can be provided for in a comparatively simple and effective manner, and thereby the typewriting machines of this class adapted for the use of the alphabets and other characters of such languages.

I claim:

- 10 1. In a typewriting machine, the combination, with the shuttle-carrying anvil and its shaft, of key-levers operatively connected therewith and provided at their outer ends with longitudinal slots, keys on said key-levers provided with shanks guided in the slots of the same, means in the path of the shift-key when the same is at one end of its slot, for limiting the downward movement of the key-lever at a predetermined position, and means in the path of the key-lever for limiting the downward movement of the key-lever at a different position when the shift-key is at the other end of its slot.
- 15 2. In a typewriting machine, the combination, with the shuttle-carrying anvil and its shaft, of a key-lever operatively connected therewith and provided with a longitudinal slot, a shift-key provided with a shank guided in said slot, and means for lowering said shift-key into two positions, an intermediate position and a lowermost position.
- 20 3. In a typewriting machine, the combination, with the shuttle-carrying anvil and shaft of the same, of key-levers operatively connected therewith longitudinally-shiftable keys, said keys being provided with shanks guided in slots of the key-levers, means for lowering each shift-key into two positions,

an intermediate and lowermost position, and springs for returning the shift-keys into 40 normal position.

4. In a typewriting machine, the combination, with the shuttle-carrying anvil and shaft of the same, of a shift-key, a key-lever operatively connected therewith, said shift-key being longitudinally movable on said key-lever, said key-lever being movable into an intermediate position and into a lowermost position, a fixed abutment in the path of the shift-key when the latter is in one 50 position on the lever, and a second fixed abutment of different length from the first in the path of the shift-key when the shift-key is in a different position on the key-lever. 55

5. In a typewriting machine, the combination, with the shuttle-carrying anvil and shaft of the same, of a shift-key, a key-lever operatively connected therewith, said shift-key being longitudinally movable on said key-lever, said key-lever being movable into 60 an intermediate position and into a lowermost position, a fixed abutment in the path of the shift-key when the latter is in one position on the lever, a second fixed abutment of different length from the first in the path of the shift-key when the shift-key is in 65 a different position on the key-lever, and means for vertically adjusting said abutments.

In testimony, that I claim the foregoing as my invention, I have signed my name in presence of two subscribing witnesses.

ARTHUR LOPEZ.
